[57] CLAIM

The ornamental design for a Bicycle freewheel core holder, as shown and described.

DESCRIPTION

FIG. 1 is a top perspective view of a bicycle freewheel core holder showing my new design;

FIG. 2 is a bottom perspective view thereof;

FIG. 3 is an elevational view thereof;

FIG. 4 is an elevational view thereof taken at right angles to the view of FIG. 3;

FIG. 5 is a top plan view thereof;

FIG. 6 is a bottom plan view thereof;

FIG. 7 is a top perspective view thereof showing parts in exploded relationship.

*Fig. 2**Fig. 1**Fig. 3**Fig. 4**Fig. 5**Fig. 6**Fig. 7*
